UNITED STATES PATENT OFFICE

GEORGE F. MEACHAM, OF NEWTON, ASSIGNOR TO JAMES W. TUFTS, OF MEDFORD, MASSACHUSETTS.

DESIGN FOR CASING OF A SODA-WATER APPARATUS.

Specification forming part of Design No. 7,771, dated September 22, 1874; application filed September 3, 1874.
[Term of Patent 14 years.]

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the lower or main portion of the casing of a soda-water apparatus, which is of rectangular form. From the center of the portion A rises a rectangular portion or tower, C, which is surmounted by a top, D, from the center of each of the four sides of which rises an ornamental projection, b. At each corner of the top is a statue, c; but these statues may be replaced by vases or other ornaments, or dispensed with altogether, if desired. In the front side of the casing, near its center, is a large circular panel, d. Extending from the wall e of the portion A to

the wall f of the portion C, on each side of the apparatus, is an incline, g, beyond the surface of which extend the arched portions h of the front and rear walls of the casing, the lower corners of which project out from the end walls e in an ornamental form, as seen at i, a unique and ornamental design being thus produced.

What I claim as my invention, and desire to secure by Letters Patent, is—

1. The design for the casing of a soda-water apparatus, substantially as herein shown and described.

2. In combination with the casing of a soda-water apparatus, the design of the ornamental top D, as shown.

Witness my hand this 29th day of August, A. D. 1874.

GEO. F. MEACHAM.

In presence of—

P. E. TESCHEMACHER,
C. E. SARGENT.
